UNITED STATES PATENT OFFICE

EDWARD WUENN, OF CHICAGO, ILLINOIS, ASSIGNOR TO THE DEARBORN COMPANY,
OF CHICAGO, ILLINOIS, A CORPORATION OF ILLINOIS

DESIGN FOR A CARD TABLE

Application filed October 14, 1929. Serial No. 33,032. Term of patent 14 years.

To all whom it may concern:

Be it known that I, EDWARD WUENN, a citizen of the United States, residing at Chicago, in the county of Cook and State of Illinois, have invented a new, original, and ornamental Design for Card Tables, of which the following is a specification, reference being had to the accompanying drawing, forming a part thereof in which—

Fig. 1 is a top plan view of the table, and Fig. 2 is an elevation showing my new design.

I claim:
The ornamental design for a card table as shown.

EDWARD WUENN.
